CLAIM

The ornamental design for vehicle wheel, as shown and described.

DESCRIPTION

FIG. 1 is a front elevation of the vehicle wheel according to one embodiment, showing my new ornamental design.

FIG. 2 is a side perspective view thereof, wherein the sides of the wheel are shown in broken lines for illustrative purposes only.

FIG. 3 is a front elevation of the vehicle wheel according to another embodiment, showing by new ornamental design; and,

FIG. 4 is a side perspective view thereof, wherein the sides of the wheel are shown in broken lines for illustrative purposes only.

Any letters, numerals or other indicia shown are by way of illustration, and do not form part of the claimed design. Shading does not form part of the claimed design, except for purposes of indicating physical contours. The side and rear views of the wheels of each of the embodiments of FIGS. 1, 2, and of FIGS. 3, 4, and do not comprise part of the claimed subject matter. Color and surface finish do not comprise part of the claimed design.
